FOLLOWER FRAME FOR LUGGAGE OR THE LIKE

Samuel J. Holtzman, 8201 Symphony Drive,
Baltimore, Md. 21208

Filed Mar. 31, 1967, Ser. No. 6,464

Term of patent 14 years

(Cl. D87—2)

FIG. 1 is an elevational view taken from one side of a follower frame for luggage or the like embodying my new design;

FIG. 2 is a top plan view thereof;

FIG. 3 is an elevational view taken from the side opposite that shown in FIG. 1;

FIG. 4 is a bottom plan view thereof;

FIG. 5 is an elevational view taken from one end thereof; and

FIG. 6 is a cross-sectional view, on an enlarged scale, taken in the plane of line 6-6 of FIG. 3.

I claim:

The ornamental design for a follower frame for luggage or the like, as shown.
